UNITED STATES PATENT OFFICE.

WILLIAM TURES, OF CHICAGO, ILLINOIS, ASSIGNOR TO THE ORO-TONE CO., OF CHICAGO, ILLINOIS, A CORPORATION OF ILLINOIS.

SOUND BOX.

Application filed June 20, 1919. Serial No. 305,614.

To all whom it may concern:

Be it known that I, WILLIAM TURES, a citizen of the United States, residing at Chicago, in the county of Cook and State 5 of Illinois, have invented certain new and useful Improvements in Sound Boxes, of which the following is a specification.

My invention relates in general to talking machines and more particularly to an 10 improved sound box.

In order that a sound box may be used both with hill and dale and zigzag records, it is necessary that it should be adjustably mounted upon a tone arm so that the plane 15 of the diaphragm may be tangent to the grooves of a zigzag record and at right angles to the grooves of a hill and dale record. It is desirable that the point of the stylus should be at the same distance 20 from the vertical axis of oscillation of the tone arm in both positions of the sound box, i. e., for zigzag and hill and dale records.

I accomplish the above desired object in my improved sound box by mounting the 25 stylus arm on the same side of the sound box as the connection with the tone arm so that the stylus may project in substantial alignment with the axis of oscillation of the sound box upon the tone arm.

A further object of my invention is to provide a sound box in which the stylus arm can be located upon the same exterior 30 side of the casing as the tone arm connection without unduly diminishing the delivery of sound waves to the tone arm.

A still further object of my invention is to provide a sound box which will be comparatively simple in construction, inexpensive in manufacture, and efficient in use.

My invention will be more fully described herein with reference to the accompanying drawing, in which the same is illustrated as embodied in a convenient and practical form, and in which—

Figure 1 is a front elevational view, the sound box being in position to play a zig-zag record;

Figure 2 is a view similar to Figure 1, looking from the rear of the sound box;

Figure 3 is a sectional view on the line 3-3 of Figure 2;

Figure 4 is an enlarged detail section through one side of the sound box, as, for instance, on line 4-4 of Figure 1; and,

Figure 5 is a detail sectional view on line 55 5-5 of Figure 2.

The same reference characters are used to designate the same parts in the several figures of the drawing.

A indicates the sound box casing which 60 comprises a cylindrical flange a projecting around the circular rear wall a¹. B indicates the diaphragm which is located within the cylindrical flange a and supported at its periphery between two gaskets C and 65 D which are preferably resilient and conveniently formed of rubber tube.

E indicates a retaining ring of channel cross section which receives within its channel the edge of the cylindrical flange a. 70 The portion of the ring E within the cylindrical flange a overlies the periphery of the diaphragm and bears upon the adjacent gasket. A plurality of spaced screws e extend through the ring E into engagement 75 with screw-threaded openings in the flange a so that by the adjustment of the screws the ring may be adjusted with respect to the flange a and the pressure imposed upon the gaskets varied so as to compensate for 80 any deterioration in the resiliency of the gaskets.

G indicates the stylus arm which is secured to the diaphragm B at the center b thereof. The stylus arm projects away from 85 the sound box casing at its lower end, where it is rigidly connected with a stylus bar H pivotally supported between lugs H¹ and H² projecting from the casing of the sound box. h¹ and h² indicate adjustable pointed screws 90 which extend through the ears H¹ and H² into engagement with recesses in the ends of the stylus bar so as to permit the latter to freely oscillate.

K indicates the usual stylus which is re- 95 movably secured in the lower end of the stylus bar by a set screw k.

M indicates an L-shaped tubular sound conduit extending from the circular rear wall a¹ of the sound box casing and communicating therethrough with the space at the rear of the diaphragm. The upper end of the conduit M is rotatably mounted within the end of the tone arm N so that the sound box may be turned substantially 90° 100 relative to the tone arm, thereby properly positioning the sound box for either hill and dale or zigzag records.

The end of the stylus arm, which is connected with the diaphragm, extends through the tubular coupling M and through the registering opening in the sound box casing, 5 through which the latter communicates with the space at the back of the diaphragm. A housing O is provided on the rear wall α^1 of the sound box casing to enclose the stylus arm G, and within such housing is suitable 10 packing P closely surrounding the stylus arm so as to minimize the escape of sound waves from the sound box around the stylus arm.

It will be observed that by locating the 15 stylus arm on the same side of the sound box casing as the conduit leading to the tone arm, the stylus may be located in substantial alignment with the axis of oscillation of the sound box upon the tone arm 20 whereby the distance of the stylus from the vertical axis of oscillation of the tone arm is substantially the same when the sound box is in both positions, i. e., for hill and dale and zigzag records.

25 It will be further observed that by my invention the diaphragm may at all times be tightly supported at its periphery within the sound box, inasmuch as compensation may be readily made for any loss of 30 silency, or any looseness which might occur in any other way, in the gaskets between which the periphery of the diaphragm is supported.

While I have described more or less precisely 35 the details of construction, I do not wish to be understood as limiting myself thereto, as I contemplate changes in form and the proportion of parts and the substitution of equivalents as circumstances may 40 suggest or render expedient without departing from the spirit of my invention.

I claim:

1. In a sound box for talking machines, the combination with a diaphragm, of a casing 45 within which said diaphragm is mount-

ed, an elbow coupling on said casing for connecting the same with the tone arm, and a stylus arm connected with the diaphragm and mounted upon the exterior of the same side of the casing with the said coupling 50 the axis of the needle in the stylus coinciding with the axis of oscillation of the sound box about its coupling.

2. In a sound box for talking machines, the combination with a diaphragm, of a casing 55 within which said diaphragm is mounted, a coupling on said casing for connecting the same with the tone arm, a stylus arm connected with the diaphragm and mounted upon the exterior of the same side of the 60 casing as that on which the said coupling is located and passing through the coupling, and a housing on the casing enclosing the stylus arm from its point of passage through the coupling.

3. In a sound box for talking machines, the combination with a diaphragm, of a casing 65 within which said diaphragm is mounted, an elbow coupling on said casing for connecting the same with the tone arm, and a stylus arm mounted upon the exterior of the 70 casing and projecting through the opening of said coupling into engagement with the diaphragm, the parts being arranged in such manner that the needle lies in the axis 75 of rotation of the sound box.

4. In a sound box for talking machines, the combination with a diaphragm, of a casing 80 within which said diaphragm is mounted, a coupling on said casing for connecting the same with the tone arm, a stylus arm mounted upon the exterior of the casing and projecting through the opening of said coupling into engagement with the diaphragm, a housing on the casing enclosing 85 the stylus arm, and a lining within said housing closely surrounding the stylus arm.

Signed at Chicago, Illinois, this 7th day of June, 1919.

WILLIAM TURES.
